AUTOMATIC RESTARTING ARRANGEMENT FOR ELECTRICALLY DRIVEN IRRIGATION PUMPS

Vernon P. Bolleson, Grand Island, Nebr.
(4529 W. 36½ St., Minneapolis 16, Minn.)
Filed Aug. 10, 1959, Ser. No. 832,763
2 Claims. (Cl. 317—13)

This invention relates generally to controls for electric motors and other electrical loads, and refers more particularly to an automatic restarting arrangement for controlling the operation of electrically driven irrigation pumps.

It is, and has for some time been, a conventional practice in agricultural irrigation to utilize electrically powered pumps equipped with solenoid operated starters for delivering water from a well or other source to a system of irrigation ditches or pipes. The availability of power through REA facilities has facilitated and encouraged such systems. However, there is at least one major problem in such operations which, so far as I am aware, has not been satisfactorily solved.

The problem arises primarily from the fact that not infrequently there is a momentary interruption in the power supply line to the pump. One of the principal causes of this phenomena is lightning. The momentary power interruption has the effect of deenergizing the starter solenoid, thus breaking the line to load contacts forming a part thereof. In conventional systems the starter remains open thereafter, even though power is restored to the line, until the starter is manually reset.

As will be evident, unless an operator is directly at hand the stopping of the motor may not be detected for some time. This has two quite discouraging consequences. The first is that no water is pumped during the interval from shut-off to discovery. The second is that once pumping is interrupted for any appreciable period it cannot be effectively commenced again until the siphon tubes have been reset, which may take as long as two hours.

It is one of the principal objects of my invention to provide a compact and fool-proof arrangement for automatically restarting electrically powered equipment of the nature described in the event of a momentary power interruption. It is a feature of my invention that the restarting is controlled solely by electrical means and requires no independent power sources such as batteries and the like. In other words, successful operation of devices according to my invention are not dependent on any parameters other than a change in the supply line voltage.

Another object of my invention is to provide a means of restarting electrical equipment of the nature described which employs a minimum of moving parts and elements and which consequently has a long operating life.

Still another object of my invention is to provide a restarting system of the character described wherein the restarting is controlled to take place only after a suitable time interval has elapsed following the interruption of power and breaking of the starter contacts. This is quite important in pumping systems, as the pumps have a tendency to reverse direction due to the suction load and will rotate in the opposite direction for a short time, should restarting be initiated before the pump has come to rest, severe and undesirable loads are placed both on the pumping equipment and the electrical system. It is a special feature of my invention that simple means are provided for preselecting different time intervals in order to accommodate the restarter to varying equipment and conditions.

A still further object of my invention is to provide a restarting arrangement of the character described which is automatically restored to its normal operating condi-

2

tion following resumption of current flow to the pump motor.

Other and further objects of the invention together with the features of novelty appurtenant thereto will appear in the course of the following description.

In the accompanying drawing the single FIGURE represents a diagrammatic showing of a typical system embodying the invention.

Referring to the drawing, reference numerals 10, 11 and 12 represent the power supply lines which are connected with a suitable source of alternating current (not shown). The supply lines are connected through switches 13, 14 and 15, respectively, with the load lines 16, 17 and 18. The load lines lead to a three-phase electric motor M which has driving connection with a conventional pump P fitted with the intake and discharge lines 19 and 20, respectively. It will be understood that the intake line 19 of the pump communicates with a suitable source of water, such as a well or the like (not shown) and that the discharge line 20 feeds through the irrigation system (also not shown).

The switches 13, 14 and 15 form a part of the solenoid operated starter for the motor M, being under the control of a solenoid 21. In this connection it should be observed that the system is shown as in a condition prior to starting of the pump motor. The switches 13, 14 and 15 are biased in conventional fashion toward the open position illustrated, but will close upon energization of the solenoid 21.

Current is supplied to a solenoid 21 through a circuit which includes supply line 10, conductor 22, main power switch 23, conductor 24, momentary push switch 25, conductors 27 and 28, solenoid 21 and conductor 29, the latter of which connects with line 11. To prepare the starter for normal operation switch 23 is manually closed. To start the motor, the momentary switch 25 is then depressed, which causes current to flow through solenoid 21. Under the influence of the solenoid switches 13, 14 and 15 will close, thus closing the line circuit to the motor. The solenoid also acts upon a normally open locking switch 30, which has the effect of locking the solenoid into an energized circuit including conductor 22, switch 23 (now closed), conductors 31 and the locking switch 30, conductor 28, solenoid 21 and conductor 29. Thus the push switch 25 may now be released without disrupting the supply of current to the motor.

The circuitry as thus far described is conventional in its general arrangement and manner of operation.

It will be evident that should any power interruption take place in the supply lines, even of a momentary nature, the solenoid 21 will be deenergized, thus permitting switches 13, 14, 15 and 30 to reassume their normal open position. The switches cannot again be closed without manually depressing the momentary switch 25 and consequently the motor would be turned off until this took place. It is the purpose of my automatic restarting arrangement to effect closing of the solenoid switches without requiring the presence of an operator in the event the power interruption is only of a momentary nature.

For the purposes of my invention I provide a step-down transformer T which has a first winding 32 connected in series between lines 10 and 11 by a circuit which includes line 10, conductor 22, switch 23, conductor 31, solenoid switch 30, conductor 27, winding 32, conductor 33, load line 17 and solenoid switch 14. It will be evident that at such times as the solenoid 21 is energized, current will flow through winding 32 of the transformer.

The second winding 32a of the transformer is connected with a rectifier R which supplies direct current to the coil 34 of an operating relay having the movable contact 35. The contact 35 is biased toward the open position shown in solid lines. Upon energization of coil 34

the contact assumes the position shown in broken lines, thus closing a circuit from the rectifier through conductor 36, contact 35, conductor 37, a capacitor 38 and conductor 39. So long as current flows through the motor M and thus through the winding of transformer T, contact 35 will remain in the broken line position and the capacitor will be charged by current supplied from the rectifier.

It will be further observed that contact 35 is arranged to open and close a circuit which includes the capacitor 38, conductor 37, contact 35, conductor 40, relay coil 41 of the control relay and conductor 39. A variable resistance 42 is connected across the capacitor and in parallel therewith. The coil 41 of the control relay acts upon the normally open contact 43 which controls a bypass line 44 across the momentary manual push switch 25. For the purposes of this application I refer to the circuit including bypass line 44 and contact 43 as the solenoid control circuit.

Assuming now that a momentary power interruption takes place, the following sequence of events occurs. Starter solenoid 21 is deenergized, thus causing starter switches 13, 14, 15 and 30 to open. Transformer T is deenergized also and consequently flow of rectified current from the rectifier ceases. Thereupon the capacitor 20 commences to discharge through relay coil 34.

The relationship and characteristics of the operating relay 34 and control relay 41 are important to an understanding of the invention. The characteristics of relay 34 must be such that its contact 35 will return to the solid line position at a time when the voltage impressed by the capacitor 38 is still high enough to cause the relay coil 41 to close its contact 43. In other words, the relay contact 35 must be set to open at a high enough voltage that the residual voltage in the capacitor, following opening 25 of the contact 35, will still be enough to bring about closing of relay contact 43 by its coil 41.

The time interval between the start of decay in the capacitor and the opening of relay contact 35 is controlled by means of the variable resistance 42. As will be evident, the lower the resistance in resistance 42 the more rapidly the voltage supplied by the capacitor will be reduced. To increase the time interval between start of decay and the opening of the contact 35 it is necessary only to increase the resistance in the variable resistance. In practice a range of time delay of from fifteen seconds to three minutes has proved satisfactory. The setting of a proper time delay will depend largely on the characteristics of the pump, the load imposed thereon and the length of time required for the motor to achieve a quiescent condition.

After the preset time interval has passed, as explained above, contact 35 moves to the solid line position and the discharge of the capacitor is directed to the control relay coil 41 causing its contact 43 to close. If the power interruption has been only momentary (less than the time delay for which the unit has been set) the closing of contact 43 again energizes starter solenoid 21. This in turn causes closing of the solenoid switches 13, 14, 15 and 30 with the result that power is again supplied from the supply lines to the motor. The winding of transformer T is at the same time energized, with the result that contact 35 is returned to its capacitor charging position represented by the broken lines. Contact 43 will, of course, open again and the entire system is reset for operation as previously described.

The provision of the variable time delay makes it possible, when a number of pumps are on the same supply line, to stagger the restarting times for the individual pumps, thus to prevent the application of too great a load at one time on the line.

Once the motor is started the only way it can be

stopped, other than by power interruption, is by means of the manual main power switch 23.

From the foregoing it will be seen that this invention is one well adapted to attain all of the ends and objects hereinabove set forth together with other advantages which are obvious and which are inherent to the arrangement.

It will be understood that certain features and subcombinations are of utility and may be employed without reference to other features and subcombinations. This is contemplated by and is within the scope of the claims.

Since many possible embodiments may be made of the invention without departing from the scope thereof, it is to be understood that all matter herein set forth or shown in the accompanying drawings is to be interpreted as illustrative and not in a limiting sense.

Having thus described my invention, I claim:

1. In an electrical system which includes a source of alternating current connected through a magnetic starter to a load, the starter having a starter solenoid and switches responsive thereto, an arrangement for automatically reconnecting the starter solenoid with the source for a predetermined interval and at a positively determined time delay following an interruption of the alternating current resulting in opening of said switches, said arrangement comprising, in combination, a solenoid control circuit including said starter solenoid and said source, a control relay, said relay having a normally open contact in said control circuit between said source and the starter solenoid, said contact operable upon closing of same to electrically connect said starter solenoid with said alternating current source, a capacitor, power conversion means connected with said system through said starter and providing a second source of power at times when said switches are closed, an operating relay connected with said second source and energized by same and having a two-position operating contact, said operating relay so constructed that the operating contact assumes a first position until the voltage impressed on said operating relay drops below a preselected value, at which time said operating contact automatically shifts to its second position, circuit means governed by said operating contact and constructed to connect said capacitor with said second source when said operating contact is in said first position and with said control relay when said operating contact is in said second position, said preselected voltage value being high enough that the voltage from the capacitor is sufficient to energize said control relay to the extent necessary to cause closing of its associated contact, and known resistance means connected in parallel with the capacitor whereby to obtain a positively controlled rate of decay in said capacitor.

2. The arrangement as in claim 1 wherein said resistance means comprises a variable resistance operable to provide for varying the rate of decay of the capacitor thus to change the time interval between failure of power at the second source and the shifting of the operating contact from its first to its second position.
